(57) **CLAIM**

The ornamental design for a connecting member for electronic washing and drying machine for laundry purpose, as shown and described.

DESCRIPTION

FIG. 1 is a front perspective view of the connecting member for electronic washing and drying machine for laundry purpose showing our new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof;

FIG. 8 is a reference view showing the state that the claimed design has been attached between the washing machine and drying machine; and,

FIG. 9 is a reference view showing the state of use that the claimed design have been attached to the electronic washing and drying machine, and then the electronic washing and drying machine have been connected by the claimed design. The broken lines depict portions of the connecting member for electronic washing and drying machine for laundry purpose that form no part of the claimed design. The portions of FIGS. 8 and 9 drawn in broken lines show environmental structure only and form no part of the claimed design.

1 Claim, 9 Drawing Sheets
